UNITED STATES PATENT OFFICE

CLARENCE D. HINDALL, OF ADA, OHIO, ASSIGNOR OF ONE-FOURTH TO THE PHILIP CAREY MANUFACTURING COMPANY, A CORPORATION OF OHIO

MECHANICAL DEVICE FOR LAYING CLOTH OR PAPER ROOF COVERINGS

Application filed March 17, 1930. Serial No. 436,530.

This invention relates to improvements in apparatus for the laying of roofing and roofing coverings.

The primary object of the invention is the provision of an improved roof laying machine, adapted to be used in connection with the laying of strip roofing covering, of cloth or paper, and so that the said covering will be provided with means to permit its adjustment incident to roof expansion.

A further object of this invention is the provision of a mechanical apparatus for the laying of cloth or paper roof covering, which is of a novel nature to crimp, either laterally or longitudinally or both, the covering as it is laid, thus providing expansion crimps adapted to compensate for expansion and contraction of the foundation upon which the roof covering is applied.

A further object of this invention is the provision of a mechanical roof covering machine adapted to be used in connection with the laying of flexible roof covering, either paper or cloth, or other composition, and embodying means to form a plurality of longitudinal expansion folds or crimps in the covering as it is laid; the improved machine embodying other structural features to permit the even laying of the covering, and means to regulate the width of the covering and also to slack the same prior to the forming of the lateral expansion folds or crimps.

A further object of this invention is the provision of a relatively simple and compact type of hand operated roof laying machine, which may be used in connection with the laying of roof coverings, including adjustments by means of which the roof covering may be provided with expansion crimps or folds notwithstanding the character of the roof structure whether corrugated or flat.

A further object of this invention is the provision of an apparatus for the laying of strip roof covering upon corrugated, standing seam, or other types of roofs, and including novel adjustable features by means of which expansion folds or crimps may be cooperatively placed according to the type of roof upon which the covering is laid.

Other objects and advantages of this in-

vention will be apparent during the course of the following detailed description.

In accompanying drawings, forming a part of this specification, and wherein similar reference characters designate corresponding parts throughout the several views,

Figure 1 is a plan view of the improved machine for the laying of roof covering, showing cooperating details thereof.

Figure 2 is a side elevation of the improved machine, showing the same in the roof covering laying position.

Figures 3, 4 and 5 are cross sectional views taken substantially on their respective lines in Figure 1 of the drawings.

Figure 6 is an enlarged sectional view taken substantially on the line 6—6 of Figure 2.

Figure 7 is a cross sectional view taken substantially on the line 7—7 of Figure 1.

Figure 8 is a fragmentary sectional view taken substantially on the line 8—8 of Figure 3.

In the drawings, wherein for the purpose of illustration is shown only a preferred embodiment of the improved apparatus adapted for the novel laying of strip roofing covering particularly on a corrugated roof the letter A may generally designate the improved machine, which may include a major frame B forwardly of which the fold or crimp forming rollers C are mounted on a shaft 20. A swinging frame D is connected forwardly to the frame B, upon which is mounted a so-called feed roller E, and a roller construction F cooperating with the crimp rollers C of the frame B in producing the folds or crimps in the roof covering. A roof covering reel G is provided upon the frame B, adapted to contain the supply of strip roofing, and in cooperative relation with other details of the machine A, as will be subsequently mentioned.

The frame B preferably comprises the side beams 10 and 11, which at their rear ends are provided with bifurcated handles 12, having hand engaging rollers or portions 13. The beams 10 and 11 are preferably parallel, and at the forward ends thereof the fold or crimp producing roller construction is

mounted. The frame beams 10 and 11, at their forward ends, between the reel construction G and the roller construction C are preferably provided with supporting wheels 15 and 16, supported upon stub shafts carried by metal straps or brackets 19 which may be affixed as at 19^a at the lower edges of the beams 10 and 11. These stub shafts 18 of the supporting wheels 15 and 16 are, of course, in transversely aligning relation upon the frame B, and it is preferred that said supporting wheels be disposed at the insides of the beams 10 and 11. They are arranged so as to not interfere with the roller construction C, nor the operation of the machine.

Referring to the crimp forming construction C, the same includes a rotatable shaft 20, mounted in suitable bearings provided in the forward ends of the beams 10 and 11. This shaft 20 is preferably removable from the beams 10 and 11. The shaft 20 fixedly supports traction wheel 21 and a plurality of specially formed wheels 23. These special wheels 23 are all of the same formation, each comprising a pair of complementary discs 25 and 26, of sheet metal, which are welded together in abutting relation. These discs 25 and 26 at their outer edges are laterally offset from the plane of the body of the discs, to provide flanges 29. When the discs 25 and 26 are assembled the flanges 29 are spaced, and at the periphery of the wheel provides a circumferential exposed groove 30, into which the wheels 32 of the roller construction F project in a cooperating fold forming relation in the roof covering, as will be subsequently described. The wheels 23 of the roller construction C are provided at their centers with threaded openings 34, adapted to threadably receive shanks 35 of sleeves 36. Each sleeve 36 is preferably provided with a set screw 37 adapted to bind against the shaft 20 to lock or key the wheels or rollers 23 upon the shaft of the roller construction C, as illustrated in Figure 5 of the drawings.

Referring to the swinging frame B the same comprises side bars 40 and 41, which are pivotally connected at their upper ends by bolts or screws 42 to the upper ends of brackets 45, which are rigidly bolted in a detachable manner at 47 to the forward ends of the rails or beams 10 and 11. The brackets 45 pivotally support the frame bars 40 and 41 so that the latter may be swung forwardly of the frame B, and upwardly thereover. The swinging bars 40 and 41 at their forward ends rotatably support a shaft 48 of the crimp producing roller construction F, in detachable manner; the ends of the shaft preferably bearing in openings provided in said swinging bars 40 and 41 and at their outer ends having detachable sleeves keyed thereto as by set bolts, as is illustrated in Figure 2 of the drawings. The roller con-

struction F cooperates with the roller construction C, and therewith is adapted to produce the crimps or the folds in the cloth or material laid upon the roof. The shaft 48 to this end supports the wheels 32, which are preferably flat, and of metal, and provided with the screw threaded central openings 49, for detachably receiving bushings 50 therein, which bear upon the shaft 48; the bushings having set screws 51 to key the same to the shaft 48 for rotation of the wheels 32 therewith. The wheels 32 at their peripheries operate in the grooves 30 of the wheels 23 of the roller construction C, and it can readily be understood that the roofing material passing between the wheels of the roller constructions C and F will be forced by the wheels 32 into the grooves 30, to longitudinally crimp the material as it passes between said rollers, and thus produce the folds or crimps as they are illustrated in Figure 5 of the drawings.

The feed roller E, is provided for the purpose of holding slack in the cloth, to take care of the folds and crimps when passing through the crimping rollers C and F, and also to hold slack in the roofing cloth or paper to accommodate the same to the corrugations of the roofing upon which the same may be laid. Such roller E is preferably a wood turning, laterally corrugated formation providing portions 55 of a diameter approximating 2 1/2", and intermediate portions 56, of a diameter approximating 1"; the portions 56 being adapted to lie in the same planes with intermeshing wheels 25 and 32 of the roller constructions C and F, as illustrated in Figure 1 of the drawings. The feed roller E, at its ends is preferably provided with detachable bolt spindles 57, which extend through slots 59 longitudinally provided in leg portions 60 of U-shaped brackets 61, at each side of the frame B; the brackets 61 including leg portions 62 which are bolted as at 63 to the arms 40 and 41 of the swinging frame D. The roller E is placed closer the pivoted ends of the frame D than the crimp providing roller construction F, and incident to the weight of the frame D bears directly toward and over the wheels 23 of the roller construction C. The cloth or roofing material from the reel G is adapted to pass between the roller construction C and the feed roller E, so that the latter presses against the said roofing material, forming the slack in the roofing material, since the said roofing material fits into the longitudinal corrugations of the roller, and holds the slack in the roofing material to permit the formation of the longitudinal crimps therein and to accommodate it to the corrugations of the roof upon which it may be laid, without liability of rupture of the roofing material incident to such formation. The roller E it is to be noted slides in a defined path along the slots 59;

the latter being obliquely positioned to the vertical, sloping upwardly from the roller construction C, so that the roller E incident to its weight moves radially towards the shaft 5 20, and most effectively cooperates in holding the slack in the roofing material as above mentioned.

The reel construction G preferably includes a sheet metal drum 65, at the ends of 10 which the retaining flanges 67 are provided; the drum 65 being adapted to have wound thereon any approved lengths of the roofing material H. The roofing material H is of course of standard width, and from the reel 15 G extends toward the roller construction C, downwardly between the peripheries of the grooved wheels 23, and the rollers E and F, and passes from the roller construction wheels 23, rearwardly, as is illustrated in Figures 3 20 and 4 of the drawings. The swinging frame D during operation is, of course, lowered forwardly of the frame B, as is illustrated in the drawings, and upon pushing of the machine by an operator the roofing material will be 25 fed from the reel G, in the relation described; the roller E producing the transverse slack in the flexible roofing covering, to compensate for the roof corrugations, and the crimps and folds provided in the roof covering by reason of the intermeshing of the wheels 32 in 30 the groove of the wheels 23. The shaft 70 of the reel G bears in suitable straps or bearings 71 carried by the rails 10 and 11, of the frame B as is illustrated in the drawings.

35 When the machine is inoperative and during transportation, the frame D is swung rearwardly toward the reel, and rests upon the beams 10 and 11, out of operating engagement with the roller construction C. During 40 such positioning the machine A can be moved upon the transportation supporting wheels 15 and 16, and the front roller construction C lifted clear of the ground or roof surface over which the machine is passing.

45 As is illustrated in Figure 5 of the drawings, the machine A produces longitudinal folds or crimps 80 in the covering material H, and the material H conforms to the shape of the roof J; the crimps or folds 80 being 50 positioned in the grooves of the roof structure J.

There are many different types of roofs, such as corrugated, and seamed, and the pitch of the corrugations and seams of which 55 vary. To this end, the wheels of the roller constructions C and F are longitudinally adjustable upon their shafts, to accommodate the spaces of the same to the pitch of the roof corrugations and seams, and the desired 60 spacing of the crimps. Of course, special feed rollers must be provided for each different adjustment, since it is preferred that this feed roller be an integral construction, and preferably corrugated longitudinally in 65 the relation shown.

As to the laying of the roof covering H, the same may be original roof covering, or may be covering placed upon already placed roofings, corrugated, seamed, flat, or otherwise shaped. In the preferred instance of placing the roof covering H, the former roofing or original roofing is painted with a special adhesive paint, and the roofing material H applied by the machine A upon this adhesive paint, and afterwards a top coating of adhesive paint is placed upon the material H.

Various changes in the shape, size and arrangement of parts may be made to the form of invention herein shown and described, without departing from the spirit of this invention or the scope of the claims.

Claims:

1. In a roofing machine the combination of means to produce crimps in the roofing material as the same is laid by said machine.

2. In a roofing machine a frame, means supported by the frame for carrying a supply of flexible roof covering, and means for producing an expansion fold in the roofing material as the same is laid by said machine.

3. In a roof laying machine the combination of a frame, means on the frame for carrying a supply of flexible roof covering, and means on the frame for producing a longitudinal expansion crimp in the roofing material as it is laid upon a roof.

4. In a roof laying machine the combination of a frame, means on the frame for carrying a supply of flexible roof covering, and means on said machine for producing a plurality of spaced parallel expansion folds in the roofing material as the latter is laid by said machine.

5. In a roof laying machine the combination of a supporting frame, means on the frame for carrying a supply of flexible roof covering, and means on the frame for transversely slackening the roof covering as it is being laid to accommodate the same to roofs of various shapes and cross sections.

6. In a roof covering machine the combination of a frame, and means on the frame to produce an expansion fold in the material as it is being laid.

7. In a roofing machine the combination of a frame, and means carried by the frame for receiving roof covering as it is being laid to transversely slack the same and shape it according to the section of the roof structure upon which the covering is being placed.

8. In a roofing machine, the combination of a frame, interfitting male and female roller constructions adapted to receive roofing material as it is being laid to provide expansion crimps in the same, and roller means cooperating with the above mentioned roller means to transversely slack the roofing material prior to passage through the interfitting male and female roller means.

9. In a roof laying machine the combina-

- tion of a frame, means on the frame to carry a supply of roof covering, means on the frame to produce a crimp in the roof covering as it is laid, and means cooperating with said last mentioned means to transversely slack the roof covering prior to passage through said last mentioned means.
10. In a machine for placing roof covering the combination of a frame, means on the frame for carrying a supply of the roof covering, interfitting wheels carried by the frame between which the roofing material is adapted to pass to produce an expansion fold therein, and means carried by the frame to transversely slack the roof material as it passes through said machine in advance of being actuated upon by said interfitting wheels.
11. In a roof covering laying machine the combination of a frame, a roller construction carried by the frame including a plurality of grooved wheels, a swinging frame carried by the first mentioned frame adjacent said roller construction, and a roller construction carried at the end of said swinging frame including wheels interfitting with the grooved wheels of said first mentioned roller construction.
12. In a roof covering laying machine the combination of a frame, a roller construction carried by the frame including a plurality of grooved wheels, a swinging frame carried by the first mentioned frame adjacent said roller construction, a roller construction carried at the end of said swinging frame including wheels interfitting with the grooved wheels of said first mentioned roller construction, and a feed roller of irregular longitudinal section movable upon said swinging frame and cooperating against the wheels of said first mentioned roller construction to transversely flex the roof covering as it is passed through said machine.
13. In a roof covering laying machine the combination of a frame, a roller construction carried by the frame including a plurality of grooved wheels, a swinging frame carried by the first mentioned frame adjacent said roller construction, a roller construction carried at the end of said swinging frame including wheels interfitting with the grooved wheels, of said first mentioned roller construction, a feed roller of irregular longitudinal section movable upon said swinging frame and cooperating against the wheels of said first mentioned roller construction to transversely flex the roof covering as it is passed through said machine, and transportation wheels carried by said frame.
14. In a roof cover laying machine the combination of a frame, a shaft rotatable at an end of said frame, traction wheels keyed to said shaft, wheels keyed to the shaft between said traction wheels having grooved peripheries, a roller construction including wheels, and means mounting the last mentioned roller construction on said frame so that the wheels thereof interfit in the grooves of the wheels first mentioned.
15. In a roof cover laying machine the combination of a supporting frame including side rails, handles at the ends of said side rails, a roller construction at the opposite ends of said side rails including a rotating shaft having traction wheels thereon and a plurality of grooved wheels, a swinging frame swingably carried at the end of said first mentioned frame adjacent said roller construction, a roller construction carried by said swinging frame including a rotating shaft having a plurality of wheels intermeshing with the grooved wheels of said first mentioned roller construction, and means carried by the frame rails for supporting a supply of roofing material.
16. In a roof cover laying machine the combination of a supporting frame including side rails, handles at the ends of said side rails, a roller construction at the opposite ends of said side rails including a rotating shaft having traction wheels thereon and a plurality of grooved wheels, a swinging frame swingably carried at the end of said first mentioned frame adjacent said roller construction, a roller construction carried by said swinging frame including a rotating shaft having a plurality of wheels intermeshing with the grooved wheels of said first mentioned roller construction, means carried by the frame rails for supporting a supply of roofing material, said swinging frame incident to its weight adapted to have the wheels of its roller construction bear against the grooved wheels of the first mentioned roller construction, and supporting wheels carried by said frame.
17. In a roof cover laying machine the combination of a supporting frame including side rails, handles at the ends of said side rails, a roller construction at the opposite ends of said side rails including a rotating shaft having traction wheels thereon and a plurality of grooved wheels, a swinging frame swingably carried at the end of said first mentioned frame adjacent said roller construction, a roller construction carried by said swinging frame including a rotating shaft having a plurality of wheels intermeshing with the grooved wheels of said first mentioned roller construction, means carried by the frame rails for supporting a supply of roofing material, said swinging frame incident to its weight adapted to have the wheels of its roller construction bear against the grooved wheels of the first mentioned roller construction, supporting wheels carried by said frame, and a feed roller longitudinally corrugated slidably in said swinging frame for normally bearing against the first mentioned roller construction to transversely slack the roof

covering as it is passed through the machine.

18. In a machine adapted to apply flexible material to a structural surface, a frame, means for supporting a supply of flexible material carried by said frame and means adapted to apply flexible material to a structural surface whereby there will be a longitudinal portion of said material out of contact with said surface between two contacting portions.

19. In a machine for placing roof covering, the combination of a frame, means on the frame for carrying a supply of the roof covering, co-acting means, carried by the frame, between which the roofing material is adapted to pass, said means producing an expansion fold therein and means between the supply and the said co-acting means to produce slack in the material as it is fed to said co-acting means.

20. In a roof covering machine the combination of a supporting frame, means on the frame for carrying a supply of flexible roofing material, running gear for the supporting frame, and interfitting male and female rollers operatively associated with the running gear for longitudinally crimping the roofing material as it passes between said rollers during the placement of the roofing material.
